UNITED STATES PATENT OFFICE.

EDWARD F. RESCHKE, OF CHICAGO, ILLINOIS.

NIPPLE.

1,122,306.

Specification of Letters Patent. Patented Dec. 29, 1914.

Application filed August 18, 1913. Serial No. 785,289.

To all whom it may concern:

Be it known that I, EDWARD F. RESCHKE, citizen of the United States, residing at Chicago, in the county of Cook and State 5 of Illinois, have invented certain new and useful Improvements in Nipples, of which the following is a specification.

This invention relates to improvements in the class of nursery devices known as baby- 10 comforters which comprise a rubber nipple with suitable means by which it can be used without danger of being swallowed by the infant. My improvements are also applicable to nipples used with nursing bottles.

15 In devices of the type to which my invention belongs, the teething infant, by biting upon the thin walls at the neck or base of the bulb, cause holes which destroy the efficiency of a nursing nipple. In some cases 20 teething infants have been known to bite the nursing or comforter nipple in two and choke upon the severed bulb portion.

In baby-comforters of commerce, it is customary to combine a teething ring with 25 the nipple.

My invention is designed to avoid the objections above mentioned and to render the teething ring superfluous.

In the accompanying drawing I have 30 illustrated preferred and modified embodiments of my invention in the following views:

Figure 1 shows a baby-comforter constructed in accordance with my invention. 35 Fig. 2 is an enlarged view, partly sectioned, of my improved baby-comforter; and Fig. 3 is a vertical section through a nursing nipple arranged upon the stopper of a bottle, the mouth only of the latter being 40 shown. Figs. 4 and 5 show a slightly modified form of my invention.

Referring to the details of the drawing, the reference character 4 represents the bulb portion of a rubber nipple, the walls of 45 which are made thin at the point and gradually increase in thickness toward the neck or base of the nipple, as clearly shown in Fig. 2.

50 5 represents annular corrugations formed in the walls of the base portion of the nipple, which are materially increased in

thickness at this portion. The surface of the corrugations is roughened by serrations which preferably extend diagonally of said corrugations and in opposite directions. 55

The usual disk or guard is shown by the reference numeral 6, and 7 represents the nipple holder or attachment, the latter being formed with a stem 7^a which is adapted to fit within the base of the nipple and is 60 given a bulbous form to prevent the too easy withdrawal of the nipple. The outer portion of the holder is provided with a hole 7^b, through which a cord 8 is strung, the latter serving to provide suitable means 65 for attaching the device to the infant's person or garments.

The holder 7 is formed of bone, celluloid, vulcanized rubber or other nonyielding substance so that the stem 7^a affords an unyielding backing for the base portion of the nipple, and thus combines with the corrugations 5 in providing the desired resistance which will facilitate the "cutting" of the infant's teeth. This action is further 75 augmented by the serrated surface of the corrugations.

Fig. 3 shows my improved nipple applied to a bottle stopper having the same functions as the comforter shown in Figs. 1 and 80 2. In said Fig. 3, the reference numeral 9 represents a nursing nipple, 9^a the corrugated nipple base, 10^a bottle stopper having a perforated stem 10 which enters the nipple and 10^b the guard, which, though not required with a bottle nipple, is shown as a means of limiting the entrance of the nipple to the infant's mouth and thus serving to confine the biting action to the corrugations adjacent the guard. 85 90

In Figs. 4 and 5, I have shown the thickened and serrated walls at the neck portion of the nipple instead of at the base or open end, the same being indicated by the reference character 5^b. 95

I am aware that nipples have been made with thickened walls at the extreme end of their mouth to increase their gripping action upon the bottle neck or other holder, but, so far as I am aware, these thickened 100 portions are not accessible to the infant's gums, while my invention contemplates the

formation of the corrugations at such portions of the nipple as may be readily received between the infant's gums whether same are at the extreme end or between the 5 end and the bulb portion.

Having thus described my invention, what I claim as new is:

A nipple having a bulb portion with easily contractible walls and a portion ad-

acent the bulb portion having thick and 10 externally roughened walls.

In testimony whereof I affix my signature in the presence of two witnesses.

EDWARD F. RESCHKE.
